(57) **CLAIM**

The ornamental design for an over the counter medicinal container with surface ornamentation, as shown and described.

DESCRIPTION

The present application file contains at least one drawing executed in color. Copies of this patent or patent application publication with color drawing(s) will be provided by the Office upon request and payment of the necessary fee.

FIG. 1 is a perspective view of a first embodiment of an over the counter medicinal container with surface ornamentation; FIG. 2 is a front view thereof;

FIG. 3 is a left side view thereof;

FIG. 4 is a back view thereof;

FIG. 5 is a right side view thereof;

FIG. 6 is a top view thereof;

FIG. 7 is a bottom view thereof;

FIG. 8 is a perspective view of a second embodiment of an over the counter medicinal container with surface ornamentation;

FIG. 9 is a front view thereof;

FIG. 10 is a left side view thereof;

FIG. 11 is a back view thereof;

FIG. 12 is a right side view thereof;

FIG. 13 is a top view thereof;

FIG. 14 is a bottom view thereof;

FIG. 15 is a perspective view of a third embodiment of an over the counter medicinal container with surface ornamentation;

FIG. 16 is a front view thereof;

FIG. 17 is a left side view thereof;

FIG. 18 is a back view thereof;

FIG. 19 is a right side view thereof;

FIG. 20 is a top view thereof; and,

(Continued)

FIG. 21 is a bottom view thereof.
 The evenly broken lines are shown for the purpose of illustrating parts of the article that form no part of the claim.
 The dot-dash lines represent the boundaries of the claim and form no part thereof.
